UNITED STATES PATENT OFFICE.

DURWARD C. COLLIER, OF BARNESVILLE, GEORGIA.

UNION SUIT.

1,146,923.

Specification of Letters Patent.

Patented July 20, 1915.

Application filed April 9, 1914. Serial No. 830,635,

To all whom it may concern:

Be it known that I, DURWARD C. COLLIER, a citizen of the United States, and a resident of Barnesville, in the county of Pike 5 and State of Georgia, have made an Improvement in Union Suits, of which the following is a specification.

My invention is an improved union suit or garment adapted for use by both women 10 and men.

The object of my invention is to provide an improved garment of this type which may be advantageously made out of tubular fabric, preferably knitted fabric composed 15 of cotton, silk, ramie, or wool.

The details of construction, arrangement, and combination of parts are as hereinafter described, and illustrated in the accompanying drawing, in which—

20 Figure 1 is a front view of my improved union suit. Fig. 2 is a rear view. Fig. 3 is a cross section on the line 3—3 of Fig. 1. Fig. 4 is a central longitudinal section on the line 4—4 of Fig. 1. Fig. 5 is a horizontal 25 section on the line 5—5 of Fig. 1. Fig. 6 is a perspective view of the bust or waist portion of the garment. Fig. 7 is a perspective view of one of the leg portions of the 30 garment. Fig. 8 is a plan view of the triangular flap forming a portion of the garment. Fig. 9 is a plan view of a piece of tubular webbing divided diagonally into two equal portions which form the legs of the garment.

35 In the principal views "A" indicates the tubular bust or waist portion of the garment, and C and D the legs of the same. These parts are all made from small tubular knitted fabric, and have the highest degree 40 of elasticity, and also afford the utmost comfort to the wearer. The distinguishing feature of the bust or waist portion A is the form of its lower edge, which, as shown in Figs. 1 to 6, is cut upon the 45 lines of a reentrant obtuse angle 1, 2, 3, on both front and back. Thus, the two front and back edges coincide or correspond. In

50 place of the cut being made on an obtuse angle it may be made upon a slightly curved line, shown in Figs. 1 and 2. In cutting the bust A in this form, a considerable number

of pieces of the tubular fabric are laid upon another so that their edges exactly coincide, or in other words, are in the same vertical plane; then a power-operated knife makes 55 a single cut through the several superposed pieces, thus forming the desired angle (Figs. 1 to 6) in both front and back of all the pieces simultaneously. It is obvious this could not be done if the front and back 60 were not alike or on the same angle.

The leg portions C and D may be formed economically or without waste, by cutting them from a single tubular fabric as shown in Fig. 9. The cut is made upon a diagonal 65 line thus producing two parts C and D which are identical in shape and size. The angular edges of the parts C, D, are sewed to the angular edge of the bust, as indicated at 1, 2, 3, in Figs. 1 and 2. Thus the angular end of each part C and D projects past the angle of the bust to a point a, as indicated in Fig. 1. It will be understood that the upper end of the leg portions C and D lie one within the other or overlap, as indicated in dotted and full lines in Fig. 2.

In cutting both the bust and legs, as described, I effect a considerable economy in time, labor, and material. The reentrant angle also conduces to the comfort of the 80 wearer of the suit, since it enables the overlapping portions of the legs to be parted or opened higher and more widely than would be practicable if the angle of the waist projected downward instead of upward or inward. This is a matter of importance when the body of the wearer assumes a sitting position.

A triangular flap B is applied on the back of the garment, as shown in Fig. 2, its upper 90 end being sewed to the bust and its inner side edge to the adjacent edge of the leg portion c. This extends to a desired degree the cover or protection afforded by the contiguous overlapping portions of the leg c. 95

What I claim is:—

1. A union suit comprising a bust or waist having its lower edge in front and back provided with coincident reentrant angles, and tubular leg portions having 100 their upper ends formed at an angle and secured to the waist so that each extends lat-

erally past the apex of the angle of the waist and overlaps the other leg portion, as described.

2. A union suit comprising a bust or waist of tubular fabric having its lower edge in front and back provided with coincident symmetrical reentrant angles having straight sides and tubular leg portions hav-

ing their upper end formed at an angle and secured to the waist so that each extends laterally past the apex of the angle of the waist and overlaps the other leg portions. 16

DURWARD C. COLLIER.
